UNITED STATES PATENT OFFICE

2,572,463

BATHTUB

William Fine, Hampton, Va.

Application February 14, 1949; Serial No. 76,234

3. Claims. (Cl. 4—173)

1

This invention relates to new and useful improvements in bath tubs and the primary object of the present invention is to provide a hollow receptacle such as a bath tub, wash basin, sink or the like having the fluid control means carried thereby and embodying novel and improved means for concealing the control means.

Another important object of the present invention is to provide a bath tub, sink, basin or the like, in which the fluid control means is concealed by a soap dish hinged to the tub and which is swingable to a position for exposing the control means.

Yet another feature of the present invention is to provide a bath tub having an upwardly curved seat portion integrally formed with the bottom wall of the tub to afford additional comfort to a user.

Another feature of the present invention is the provision of a bath tub having spaced inner and outer side walls between which there is provided a storage compartment, said outer side walls having openings and closures for the openings.

Another feature of the present invention is to provide a bath tub wherein the fluid control means are located at one side of the tub in a conveniently accessible position.

Another feature of the present invention is the provision of a bath tub having a combination fluid supply and drain that are selectively actuated for the delivery of water into the tub or for the removal of water from the tub.

A further object of the present invention is to provide a bath tub, wash basin, sink or the like that is extremely neat and attractive in appearance and which is provided with storage compartments for receiving clothes or other such articles.

A still further aim of the present invention is to provide a bath tub that is simple and practical in construction, strong and reliable in use, relatively inexpensive to manufacture, and otherwise well adapted for the purposes for which the same is intended.

Other objects and advantages reside in the details of construction and operation as more fully hereinafter described and claimed; reference being had to the accompanying drawings forming part hereof, wherein like numerals refer to like parts throughout, and in which:

Figure 1 is a perspective view of the present bath tub and showing the closure in open position;

Figure 2 is a transverse vertical sectional view taken substantially on the plane of section line 2—2 of Figure 1;

Figure 3 is an enlarged vertical sectional view taken substantially on the plane of section line 3—3 of Figure 2; and

Figure 4 is a fragmentary perspective view of the present invention and showing the main closure or soap dish in a closed position.

Referring now to the drawings in detail, wherein for the purpose of illustration, there is dis-

2

closed a preferred embodiment of the present invention, the numeral 10 represents the present bath tub generally, including an elongated hollow body or receptacle having a bottom wall 12, spaced inner and outer side walls 14 and 16, and an upper wall 18 that is integrally formed with the side walls 14 and 16 at the upper ends thereof. The outer side walls 16 extend well below the bottom wall 12 and have lower, straight edges 20 that bear upon the floor surface 22 in order to support the tub 10 in a substantially horizontal position.

For the purpose of description, one of the outer side walls of the tub 10 will be referred to by the numeral 24 and one inner side wall of the tub will be indicated by the numeral 26, since these walls are spaced from each other slightly greater than the distance between any other pair of inner and outer side walls, for a purpose which will later be more fully described.

Due to the increased spacing between the side walls 24 and 26, the portion 28 of the upper wall 18 is also increased in width but not sufficiently to disturb the normal balance and neat appearance of the tub.

The bottom wall 12 is pressed upwardly at one end to provide a smoothly contoured, raised, seat portion 30 and the bottom wall 12 slopes downwardly from both longitudinal sides to its longitudinal center for drainage purposes.

At the center and low point of the bottom wall 12, there is provided an opening 32 that receives the reduced internally threaded neck portion 34 of a cap or nozzle 36 having openings 38 that are disposed above the inner surface of the bottom wall 10 at its low point, so that water in the tub may pass through the openings 38 into the tub, so that water forced into the cap can pass into the tub through the openings 38.

A receptacle or cup 40 is provided with a threaded open end 42 that receivably engages the neck 34 and an externally threaded rib 44 that receivably engages a washer 46. A resilient washer 48 embraces the cup 40 and is clamped by the nut 46.

The cup 40 is provided with a pair of vertically spaced openings 50 and 52 the lower of which (52) is tangent to the inner surface of the cup's bottom wall 54 so that any water entering the cup would be drained therefrom by way of the opening 52. Obviously, the bottom wall 54 could be shaped so as to drain all water in the cup through opening 52 to prevent sedimentation collecting in the said cup, although the relative velocity of water entering the cup will be sufficient, under normal conditions, to effectively wash from the cup any sedimentation collecting therein.

A drain conduit 56 extends from the port or opening 52 and is provided with a suitable valve 58 having a trip lever 60. An operating rod 62 is pivoted to the lever 60 and includes an extension 64 that is slidably received by a guide sleeve or bearing 66 carried by the lower wall 68 of

a recess 70 formed in the portion 28 of the upper wall 18. A knob or finger grip 72 fixed to the extension 64 is raised to actuate the lever 60 to a valve open position and lowered to actuate the lever 60 to a valve closing position. It being understood, that sufficient looseness is provided between the sleeve 66 and extension 64 to permit the lever 60 to swing upwardly and downwardly enough to open and close the valve 58.

A perforated overflow drain cup or sleeve 74 is fixed to the side wall 26, beneath the recess 70, and is coupled to an overflow conduit 76 that leads to a suitable sump or sewer line, and which is connected to the conduit 56 to reduce the number of pipe lines required.

A supply conduit 78 extends to the port or opening 50 and slopes downwardly toward the cup 40 to prevent backwashing of water into the conduit 78. The conduit 78 is connected in a usual manner to hot and cold water pipes, one of which is shown in Figure 2 and illustrated by the numeral 80, and valves 82 control the supply of hot and cold water to the conduit 78. The valves 82 are regulated by control rods 84 that are journaled in guide sleeves or bearings 86 carried by the lower wall 68 of the recess 70. Handles or hand grips 88 are carried by the rods 84 and disposed in the recess 70.

Also positioned in the recess 70, is a further hand grip or handle 90 that controls or switches the supply of water from the tub to a shower head (not shown) in a manner well known in the art.

The upper portion of the side wall 26 is provided with or integrally formed with spaced sleeves or knuckles 92 that are lined with further sleeves or knuckles 94 at one side wall of the substantially rectangular closure or soap dish 96. A suitable hinge pin joins the knuckles 92 and 94 to permit swinging movement of the closure 96 into the tub or into the recess 70.

When the closure 96 is swung into the recess 70, or to a position overlying the bottom wall of the recess 70, the base wall 98 of the closure is flush with the upper surface of the portion 28 and the sides of the closure 96 are flush with the walls 24 and 26 to eliminate any harmful projections and to add to the attractiveness of the entire tub structure.

The ends of the closure 96 are formed with drainage openings 100 whereby any fluid collecting in the said closure 96 will drain therefrom before the same is moved to a position for concealing the hand grips 72, 88 and 90.

In order to raise the closure 96, there is provided a recess 102 in the wall 24, adjacent the recess 70, facilitating access to the free side wall of the closure 96.

Suitably fixed between the side walls 24 and 26 is a plurality of vertically spaced panels or shelves 104. The side wall 24 is also provided with an excess opening 106 for the shelves 104 and closures or doors 108 hinge to the side wall 24 and normally close the opening 106.

A further opening 110 is provided in the wall 24 and slidably receives the substantially triangular side walls 112 of a hamper 114. It being understood that any suitable means is applied to the rear wall 116 of the hamper 114 to limit swinging movement thereof relative to the wall 24, such as sliding latches carried by the wall 116 that will bear against the inner surface of the wall 24 when the hamper is moved to its open position.

Since the present tub is to be anchored in a

room area, the outer side walls 16 are also formed with weight reducing openings 118 eliminating an unnecessary quantity of material required for the molding of the present tub.

Obviously, the present structure could be easily incorporated in the structure of a sink or wash basin by merely changing the relative size of the article disclosed. When utilized in this latest capacity, the storage compartments will receive razor blades, toothbrushes or other such toilet articles.

It should be noted, that the present tub may be applied so that one of its sides abuts a vertical wall; one of its end walls and one of its side

walls abut a pair of adjacent perpendicularly disposed vertical walls; both of its end walls and one of its side walls abut a pair of spaced vertical walls and a further wall between the pair of walls; the tub may be recessed in a floor or may be disposed upon the floor and spaced from all walls of a room.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A receptacle comprising a body member having a bottom wall and continuous inner and outer side walls, an upper wall joining said side walls and having a recess therein, fluid control handles carried by the upper wall and positioned in said recess, and a soap container hinged to said inner side wall and forming a closure for said recess.

2. In a bath tub including an upper wall and associated fluid control handles, means for concealing the handles comprising a recess provided in said upper wall and receiving said handles, and a soap dish hinged to said tub and normally overlying said recess and enclosing said handles.

3. The combination of claim 2 wherein said dish includes a base portion that is coplanar with the upper wall of said tub when the former overlies said recess.

WILLIAM FINE.
